DESIGN FOR A CIGARETTE LIGHTER

George Mulligan, New York, N. Y., assignor to Platinum Products Company Inc., New York,
N. Y., a corporation of New York

Application December 3, 1935, Serial No. 59,886

Term of patent 14 years

To all whom it may concern:

Be it known that I, George Mulligan, a citizen of the United States and resident of New York city, in the county and State of New York, have invented a new, original and ornamental Design for a Cigarette Lighter, of which the following is a specification, reference being had to the accompanying drawing, forming part thereof.

lighter showing my new design.

Figure 3 is a perspective rear view.

I claim:

The ornamental design for a cigarette lighter substantially as shown.

GEORGE MULLIGAN.
